(57) **CLAIM**

The ornamental design for a planter and package combination, as shown and described.

DESCRIPTION

FIG. 1 is a top, front, right perspective view of a planter and package combination according to our new design;

FIG. 2 is a bottom, rear, right perspective view of the planter and package combination of FIG. 1;

FIG. 3 is a top plan view of the planter and package combination of FIG. 1;

FIG. 4 is a bottom view of the planter and package combination of FIG. 1;

FIG. 5 is a front side elevation view of the planter and package combination of FIG. 1; the rear side elevation view is a mirror image thereof;

FIG. 6 is a left side elevation view of the planter and package combination of FIG. 1; and,

FIG. 7 is a right side elevation view of the planter and package combination of FIG. 1.

The evenly spaced broken lines in the drawing depict portions of the planter and package combination that form no part of the claimed design; the dot-dash-dot broken lines depict the boundaries of the claim and form no part thereof.
